DESIGN FOR AN ILLUMINATING PROJECTOR

William F. Peck, Snyder, N. Y., assignor to
Spencer Lens Company, Buffalo, N. Y., a cor-
poration of New York

Application March 7, 1941, Serial No. 99,405

Term of patent 3½ years

To all whom it may concern:

Be it known that I, William F. Peck, a citizen
of the United States, residing at Snyder, in the
county of Erie and State of New York, have in-
vented a new, original, and ornamental Design
for an Illuminating Projector, of which the fol-
lowing is a specification, reference being made
to the accompanying drawing forming a part
thereof.

Fig. 1 is a front view of an illuminating pro-
jector showing my new design;

Fig. 2 is a side view thereof; and
Fig. 3 is a bottom view thereof.

The essential features of my design are shown
in full lines, the parts shown in broken lines
in Fig. 1 have been omitted in Figs. 2 and 3 for
convenience of illustration.

I claim:

The ornamental design for an illuminating
projector, substantially as shown and described.

WILLIAM F. PECK.
